UNITED STATES PATENT OFFICE.

ROY W. SMITH, OF MECHANICVILLE, NEW YORK.

HELICOPTER FLYING MACHINE.

Application filed January 10, 1923. Serial No. 611,776.

To all whom it may concern:

Be it known that I, ROY W. SMITH, a citizen of the United States, residing at Mechanicville, in the county of Saratoga and State of New York, have invented certain new and useful Improvements in Helicopter Flying Machines, of which the following is a specification.

This invention relates to helicopter flying machines of that class embodying a plane and elevating and propelling means.

The object of my invention is to combine the plane with elevating means of the paddle wheel type in such manner that the air pressure above the plane will be relieved and the air pressure underneath the plane greatly augmented so that the flying machine is, in effect, blown upwardly from beneath and, only meeting with greatly decreased air pressure above, rises easily to the desired height.

Suitable propelling means for driving the machine is employed.

Preferably, means will be employed to hold the paddle wheels in stationary position, when they have elevated the machine to the proper height for flying, to the end that certain of their blades or vanes will constitute continuations of the plane while the machine is in flight and thus augment the supporting effect of the plane.

To prevent injury to, or death of, the aviator due to stalling of the engine when the machine is in flight, means are provided whereby the engine may be released so that it will fall by gravity to the earth, completely free of the machine, thereby enabling the machine to descend without any danger to the aviator.

The invention is susceptible of modification without departing from the essential principles thereof and the disclosure is to be considered as illustrative of the invention and not in limitation of its scope.

The invention may be embodied in a toy flying machine with, or without, employment of the engine releasing means.

In the accompanying drawings:

Figure 1 is a side elevation;

Fig. 2 a plan view;

Fig. 3 an end elevation; and

Fig. 4 is a detail view.

The frame 1 supports the curved plane 2, which may be of any suitable material or fabric, the propellers or elevating paddle wheels 3, and the engine or motor 4.

The frame 1 will be so constructed and proportioned that the engine or motor 4 will be located sufficiently far below the plane 2 to insure stability of the machine when rising and when in flight.

The engine or motor 4 is carried by a sub-frame or platform 5 which is releasably connected to the frame 1 and controlled by suitable means such, for instance, as a lever 6 which may be operated if the engine stalls and thus release the engine or motor from frame 1 so that it will fall to the earth, after which the machine will gradually descend, or parachute down, without injury to the 70 aviator, thus entirely eliminating what has heretofore been a serious menace in all types of aeroplanes and flying machines.

The elevating paddle wheels 3 are arranged in pairs, each being composed of frames carrying suitable material or fabric and, in the present embodiment thereof, the paddle wheels are secured to a shaft 7, in each instance. The shafts 7 rotate in suitable bearings 8 carried by extensions of the frame 1, the arrangement being such that the vanes of the paddle wheels rotate closely to, but do not touch, the margins of the plane 2, when said paddle wheels are revolving for the purpose of elevating the machine. On the other hand, when the machine has ascended sufficiently for horizontal flight, the paddle wheels may be locked so that certain ones of their vanes will constitute, in effect, continuations of the plane 90 2, thus increasing the effective supporting plane area while the machine is in flight.

The shafts 7, and the paddle wheels 3, are driven from the engine or motor 4 in such manner that said paddle wheels revolve in the direction indicated by the arrows, that is, one set of paddle wheels revolves in a clockwise direction and the other set in a counter-clockwise direction. The effect of this operation is to draw the air away from the top of the plane 2 and to blow it under the plane 2. By decreasing the air pressure on top of the plane 2 and blowing the air against the under side of said plane, the machine is, in effect, blown upwardly, resulting in adaptability to ascend whereas if the air pressure on top of the plane 2 was not relieved such ascent would not be obtainable. Furthermore, by providing elevating paddle wheels on both sides of the machine, the air pressure above the plane 2 is equally relieved over the entire area of said plane and

the air pressure is equally increased over the entire under-area of the plane. This results in an even elevation of the machine and minimizes tendency to tilt.

5 I prefer to drive the shafts 7 from the engine or motor 4 by shafts 9 and 10 having geared connections 11, 12, to the shafts 7 and gears 13, 14, operated by a gear 15, driven by the shaft of the engine.

10 A suitable clutch and lever 16 constitute means for coupling or uncoupling the gear 15 so that the paddle wheels 3 may be driven or stopped. Suitable locking means 17 is employed for the purpose of locking the 15 paddle wheels when stationary so that certain of their vanes will be arranged as continuations of the plane 2 and thus afford additional plane area for sustaining the machine when in flight.

15 For the purpose of propelling the machine, any suitable propelling means may be employed. There is shown a single propeller 18, and a lever operated clutch 19 for rendering said propeller operative or inoperative.

20 When the machine is to ascend, preparatory to flight, the locking means 17 will be released and the lever 16 operated to couple the gear 15 so that when the engine is started the paddle wheels 3 will revolve in the directions indicated by the arrows. The machine will then ascend by reason of the relief of the air pressure above the plane 2 and the augmenting of the air pressure below said 25 plane. When the machine is on the ground, the air will be blown against the ground as well as up against the under surface of the plane 2, affording additional elevating power for the machine. Thereafter, the relief of 30 the pressure above the plane 2 and increase of the pressure below the plane will, in effect, blow the machine upwardly under stable conditions until the proper altitude has been attained for flight. The lever 16 35 will then be operated to uncouple the drives to the paddle wheels 3 and said paddle wheels

may then be locked by the means 17 for the purpose hereinbefore described. The clutch 19 having been thrown in, the engine turns the propeller 18 and the machine will 50 then fly.

I claim:

1. In a helicopter flying machine, the combination with a plane having unobstructed opposite margins, of elevating paddle wheels 55 arranged adjacent and beyond the said unobstructed opposite margins of said plane, and means for revolving said paddle wheels in opposite directions for the purpose of relieving the air pressure above the plane 60 and blowing air underneath the plane against its under surface.

2. In a helicopter flying machine, the combination with a plane having unobstructed opposite margins, of elevating paddle wheels 65 arranged to revolve on horizontal axes adjacent and beyond the said unobstructed opposite margins of said plane, and means for revolving said paddle wheels in opposite directions for the purpose of relieving the 70 air pressure above the plane and blowing air against the under surface of said plane, said paddle wheels being adapted to be arranged so that certain of their vanes will constitute continuations of the plane when 75 said paddle wheels are stationary.

3. In a helicopter flying machine, the combination with a plane having unobstructed opposite margins, of elevating paddle wheels 80 arranged adjacent and beyond the said unobstructed opposite margins of said plane, an engine or motor located below the plane, and driving connections from said engine or motor to said paddle wheels acting on them centrally of their lengths and 85 adapted for revolving the paddle wheels in opposite directions for the purpose of relieving the air pressure above the plane and blowing air underneath the plane against 90 its under surface.

In testimony whereof I affix my signature.

ROY W. SMITH.
